UNITED STATES PATENT OFFICE.

ALEXANDER MCKELLAR, OF CUMNOCK, SCOTLAND.

PIN-POINT PROTECTOR.

1,174,079.

Specification of Letters Patent.

Patented Mar. 7, 1916.

Application filed August 16, 1913. Serial No. 785,147.

To all whom it may concern:

Be it known that I, ALEXANDER MCKELLAR, of 4 Glaisnock street, Cumnock, Scotland, watchmaker and jeweler, have invented certain new and useful Improvements in Pin-Point Protectors, of which the following is a specification.

This invention has for its object to provide a simple and effective device for the protection of pin points, and as a safeguard against the loss of articles of jewelry, such as brooches, scarfpins, and the like, and also to prevent the pin-point tearing vest or neck-tie when in use.

15 In the drawings accompanying the specification I have shown the invention applied to a brooch as illustrating one example of its application.

Figure 1 is a back view of a brooch embodying my invention. Fig. 2 is a plan of the same showing the brooch fastened by the pin to which the improvements embodying my invention are applied. Fig. 3 is a corresponding view showing the brooch unfastened by the pin and the improved device detached from the point of the pin. Fig. 4 is a back view of the brooch embodying my invention in one of its alternative or modified forms. Fig. 5 is a plan corresponding to Fig. 2 showing the brooch fastened by the pin to which the modified form is applied, the dotted lines illustrate the safeguard and protector removed from the point of the pin. Fig. 6 is an end view of the same, all hereafter more fully referred to and described.

Referring to the drawings which illustrate my invention as applied to a brooch, the device consists of a finely coiled spiral spring A made of hard drawn wire and formed so as to grip the end of the pin B of the brooch B¹. In its present application there is a short chain C, one end of which is attached to a small ring D fixed to the brooch B¹ and the other to the spiral spring A whereby, even when the brooch becomes unfastened, there is a prevention against its falling from the dress of the wearer.

According to the modification illustrated in Figs. 4, 5 and 6, the end of the spring A is formed into a loop E to which one end of the chain C is fastened, and from the loop the wire is bridged across the spring and suitably fixed to the end thereof. In the 55 bridge-piece F a wave or bend G is provided

to enable the free end of the catch H, on the brooch, or the like, to pass through it, when the brooch, or the like, is fixed to the garment of the wearer. A half turn of the spring is then made carrying the bridge-piece with it, so that the wave, or bend G engages the catch H and being looped is turned into the position shown in Fig. 6, which operation forms an effective lock, and the brooch, or the like, cannot possibly be detached from the garment until the spring has been again turned in the opposite direction and the catch unlooped from the said wave or bend G. In its application to pendants there would be a short pin fixed to the back of pendant to which the grip is fastened after the pin is inserted in the dress. The grip may be arranged in various designs to suit the special purpose of its application, e. g. as a protection to pin points, it can be so enlarged as to represent a sword handle, a golf club blade, or any other device of an ornate nature.

In using my invention on pin points, the grip is simply fixed on the end of the pin, and a half-turn of the spring-grip tightens the grip so that it will not slip off until it is unloosened by the reverse movement. This method of fixing the grip is also applicable to the various other uses above described.

Claim.

A device for safeguarding scarf pins, pendants, and the like, comprising in combination a brooch, a pin pivoted to said brooch, a hook-like catch for said pin, and a combined guard and lock for said pin, said guard and lock being formed of a closely coiled spiral wire adapted to fit over the end of the pin and tapering toward the point of the pin, said wire being formed into a loop at the larger end of the spiral, and being bridged across from the said loop to the smaller end of the spiral, the bridging portion of said wire being bent outward away from the coiled portion of the wire in a U-like bend adapted to inclose said catch and lock said guard and pin thereto, and chain connecting said brooch and said loop.

In testimony whereof I affix my signature in presence of two witnesses.

ALEXANDER MCKELLAR.
